Primary Examiner — David Muller(74) Attorney, Agent, or Firm — Frank D Lachenmaier;
Lachenmaier Law Firm(57) CLAIM

The ornamental design for a detachable air flow deflector, as shown and described.

DESCRIPTION

FIG. 1 is a perspective front lower view of ductless split Air Conditioning wall unit with two strips of hook fasteners adhered to Air Conditioning Wall Unit as shown.

FIG. 2 is a perspective front lower view of ductless split Air Conditioning wall unit with detachable air flow deflector attached by connecting the two strips of hook fasteners to the two strips of eye fasteners.

FIG. 3 is an enlarged view in the broken line circle showing the two strips adhered to ductless split Air Conditioning wall unit.

FIG. 4 is an enlarged view in the broken line circle showing the attachment of detachable air flow deflector by connecting the two strips of eye fasteners to the two strips of hook fasteners; and,

FIG. 5 is a top view of detachable air flow deflector as a rectangular sheet of thin walled transparent plastic with strips of eye fasteners adhered on the long sides of the rectangle, prior to attachment to Air Conditioning wall unit. A ductless split Air Conditioning wall unit is shown in broken lines in FIGS. 1, 2, 3 and 4 as it is not part of this invention and is shown for environmental purposes only, as is the corner of the room that the wall unit is mounted in.
